UNITED STATES PATENT OFFICE

108,232

DESIGN FOR A COASTER WAGON

Clarence E. Garton, Sheboygan, Wis.

Application April 17, 1937, Serial No. 68,836

Term of patent 3½ years

To all whom it may concern:

Be it known that I, Clarence E. Garton, a citizen of the United States, residing in the city of Sheboygan, in the county of Sheboygan and State of Wisconsin, have invented a new, original, and ornamental Design for a Coaster Wagon, of which the following is a specification, reference being had to the accompanying drawing, forming part thereof.

The dominant feature of the design consists in the disclosure in full lines.

I claim:

The ornamental design for a coaster wagon, as shown and described.

CLARENCE E. GARTON.
